UNITED STATES PATENT OFFICE

164,776

COMBINATION ELECTRIC HEATER AND FAN CASING

Charles E. Jones, Chicago, and Robert H. Crowle,
Berwyn, Ill., assignors to Cory Corporation,
Chicago, Ill., a corporation of Delaware

Application April 18, 1951, Serial No. 14,882

Term of patent 14 years

(Cl. D81—10)

To all whom it may concern:

Be it known that we, Charles E. Jones and Robert H. Crowle, citizens of the United States, residing at Chicago and Berwyn, respectively, in the county of Cook and State of Illinois, have invented a new, original, and ornamental Design for a Combination Electric Heater and Fan Casing, of which the following is a specification, reference being had to the accompanying drawing, forming a part hereof.

In the drawing:

Fig. 1 is a front elevation of a combination electric heater and fan casing showing our new design;

Fig. 2 is a side elevation;

Fig. 3 is a top plan view; and

Fig. 4 is a perspective view of the casing with the front hood forming portion in extended relation.

The essential features of our design reside in the portions shown in full lines.

We claim:

The ornamental design for a combination electric heater and fan casing, as shown and described.

CHARLES E. JONES.
ROBERT H. CROWLE.
